(57) **CLAIM**

The ornamental design for a side repeater light of a truck vehicle, as shown and described.

DESCRIPTION

FIG. 1 is a right, front perspective view of a side repeater light of a truck vehicle showing our new design, with the wires broken away at the end to indicate indeterminate length;

FIG. 2 is a left view thereof;

FIG. 3 is a right view thereof;

FIG. 4 is a front view thereof; and,

FIG. 5 is a top view thereof.
